(57) **CLAIM**

The ornamental design for an interface dock, as shown and described.

DESCRIPTION

FIG. 1 is a top perspective view of an interface dock showing my new design;

FIG. 2 is a top view thereof;

FIG. 3 is a left side view thereof;

FIG. 4 is a right side view thereof;

FIG. 5 is a front view thereof;

FIG. 6 is a rear view thereof; and,

FIG. 7 is a bottom view thereof.

The broken lines immediately adjacent to the shaded areas form unclaimed boundaries of the design. The broken line showing of the recessed region and the remainder of the interface dock is for environmental purposes only and forms no part of the claimed design.
